Primary Examiner — Joseph Kukella*Assistant Examiner* — Heather Wencl(74) *Attorney, Agent, or Firm* — Sanchelima & Associates, P.A.; Christian Sanchelima; Jesus Sanchelima(57) **CLAIM**

The ornamental design for a clothing safety harness, as shown and described.

DESCRIPTION

FIG. 1 is a front elevational view of a clothing safety harness shown open, in a configuration of use;

FIG. 2 is a front elevational view shown fastened;

FIG. 3 is a rear elevational view thereof;

FIG. 4 is a left side elevational view thereof;

FIG. 5 is a right elevational view thereof;

FIG. 6 is a top plan view thereof; and,

FIG. 7 is a bottom plan view thereof showing our design. No claim is made to the firefighter suit shown in broken lines, it is shown for illustrative purposes only.

1 Claim, 7 Drawing Sheets(56)
